US00D467565S

(12) **United States Design Patent** (10) Patent No.: **US D467,565 S**
 Pesqueira et al. (45) Date of Patent: **** Dec. 24, 2002**

(54) **RADIO TRANSCEIVER**

(75) Inventors: **Mark Richard Pesqueira**, Chicago, IL (US); **Jimmy-Quang Viet Doan**, Chicago, IL (US); **Erin Marie Napolitano**, Chicago, IL (US); **Frank Poggio**, Hoffman Estates, IL (US)

(73) Assignee: **Cobra Electronics Corporation**, Chicago, IL (US)

(**) Term: **14 Years**

(21) Appl. No.: **29/152,320**

(22) Filed: **Dec. 17, 2001**

(51) LOC (7) Cl. **14-03**

(52) U.S. Cl. **D14/137**

(58) Field of Search D14/137, 138, D14/218, 147-148, 247-248, 144, 155, 159, 341-347, 358, 188, 192-198; 379/433.01-433.13, 419, 434, 428.01-428.04, 420.01-420.04, 440; 455/550-575, 90, 347, 350, 351; D21/517

(57) **CLAIM**

The ornamental design for a radio transceiver, as shown and described.

DESCRIPTION

FIG. 1 is a perspective view of a radio transceiver.

FIG. 2 is a front view of the radio transceiver of FIG. 1.

FIG. 3 is a first side view of the radio transceiver of FIG. 1.

FIG. 4 is a second side view of the radio transceiver of FIG. 1.

FIG. 5 is a rear view of the radio transceiver of FIG. 1.

FIG. 6 is a top view of the radio transceiver of FIG. 1; and, FIG. 7 is a bottom side view of the radio transceiver of FIG. 1.

The broken line showings in the views are for illustrative purposes only and form no part of the claimed design.
